UNITED STATES PATENT OFFICE.

WILLIAM HENRY BURNS, OF NAPERVILLE, ILLINOIS.

ELECTRIC INSOLE.

No. 892,360.

Specification of Letters Patent.

Patented June 30, 1908.

Application filed July 11, 1907. Serial No. 383,351.

To all whom it may concern:

Be it known that I, WILLIAM HENRY BURNS, citizen of the United States, residing at Naperville, Illinois, have invented certain new and useful Improvements in Electric Insoles, of which the following is a specification.

My invention relates to improvements in electric soles and has for its object to provide an inner sole for boots and shoes which will produce more effective circulation of an electric current than those heretofore produced of which I am aware; and which will occupy a minimum amount of space, and which will not require any special pockets or recesses, and will not tend to produce any uneven places on the interior of the shoe where the sole of the foot rests.

With these and possibly other objects in view the invention includes the novel features of construction and arrangement of parts hereinafter described and particularly set forth in the appended claims.

An embodiment of the invention is illustrated in the accompanying drawing, in which,

Figure 1 is a plan view, and Fig. 2 a side elevation partly in section. Fig. 3 is a plan view of the plates separated.

Referring by reference characters to this drawing, the numeral 4 designates the improved sole which is composed of two plates 5 and 6, the one (5) of copper and the other (6) of zinc. These are formed, each of a single piece of material with a continuous rim and alternating bars and spaces as clearly shown in Fig. 3.

The bars and spaces of both plates are arranged at an angle or inclination to the line of the foot, and are arranged so that when one of the plates is placed upon the other the bars 5^a of the plate 5 will come opposite the

spaces 6^b of the other plate and vice versa, the bars 6^a opposite the spaces 5^b.

The two plates are secured together by a line of copper rivets extending around the outside, as shown at 7. By this construction and arrangement I provide an insole in a galvanic couple extending over the entire surface of the sole of the foot and without any uneven parts, and without the necessity of providing any recesses or the like in the sole of the boot or shoe.

I may sometimes find it desirable to provide a layer of insulating material, such as rubber, on the under side of the galvanic couple as indicated at 8.

It will be understood that the foot of the wearer contacts with the upper plate and protrudes between the space therein into contact with the lower plate also thereby an external circuit is produced through the foot of the wearer. The perspiration or moisture from the foot of the wearer between the junction of the two metals forms an electrolyte which produces an electric current thus making an internal circuit in the cell.

Having thus described my invention, what I claim is:

An electric insole comprising a pair of superposed metallic plates each of which has alternating bars and spaces, the bars of one plate being in alinement with the spaces of the other so that the foot of the wearer contacts upon the bars of the upper plate and protrudes through the spaces therein into contact with the bars of the lower plate.

In testimony whereof, I affix my signature in presence of two witnesses.

WILLIAM HENRY BURNS.
